METHOD OF FORMING SHEET METAL ARTICLES

Ivar A. Morberg, Chicago, Ill., assignor to Western Electric Company, Incorporated, New York, N. Y., a corporation of New York

Application January 11, 1936, Serial No. 58,635

3 Claims. (Cl. 113—116)

This invention relates to a method of forming sheet metal articles, and more particularly to a method of forming the lower housings of telephone coin collectors.

5 It is an object of the present invention to provide an inexpensive method of producing a strong and durable structure for enclosing coin receptacles.

In accordance with one embodiment of the 10 invention as applied to the lower housing of telephone coin collectors which houses the coin receptacle, a blank is cut from sheet metal stock and drawn to a hollow substantially rectangular configuration intended to serve as the front and 15 portions of the side, top and bottom walls of the lower housing. The blank is then perforated to form a door opening and partially form a coin chute opening, whereupon the edges of the door opening are drawn backwardly out of the plane 20 of the front of the rectangular detail and the coin chute opening is sheared and the side of the sheared portion partially formed out of the plane of said front. In the next step the edges of the door opening are trimmed to remove some 25 of the excess metal, and finally the sheared portion of the front is bent at right angles to the front, and the edges of the door opening swaged to form a seat for the door. After the front half of the housing is formed in this manner, 30 it is welded to the rear portion of the coin box.

A better understanding of the invention may be had by reference to the following description when considered in conjunction with the accompanying drawing, wherein

35 Fig. 1 is an isometric projection of the lower housing of a telephone coin collector having a front portion formed in accordance with the present invention;

40 Fig. 2 is an isometric projection of a blank sheared from stock and formed in accordance with the first step of the invention, parts being broken away to more clearly illustrate the configuration of the blank, and

45 Figs. 3, 4 and 5 are views similar to Fig. 2 illustrating the successive steps in forming the front half of the coin box.

50 Referring now to the drawing wherein like reference characters indicate the same parts throughout the several views, particular reference being had to Fig. 1 wherein a lower housing 10 for a telephone coin collector comprises a front portion and a rear portion indicated generally by the numbers 11 and 12, respectively. When this housing is in use it is secured

5 to a base or back plate and encloses a coin receptacle, a door being inserted in the opening 13 in the front portion 11. The base or back plate, door, and upper portion which supports the telephone apparatus have not been shown since they are well known and do not form part of the present invention.

The rear portion 12 of the housing may be made from a flat sheet of metal bent and formed so as to provide a bottom having a plurality of 10 strengthening ribs 14, only one of which is visible in Fig. 1, sides 15 and 16, upper flanges 17 and 18 and rear flanges 19, only one of which is shown in Fig. 1.

The front portion 11 of the housing comprises 15 a flat top 25, a front wall 26 and an angularly disposed portion 27, all formed from a single sheet of metal. The front portion also includes a bottom 28 and sides 29 and 30 and has in addition to the door opening 13, a coin chute 20 opening 31 through which coins, which have been deposited by a user, may be withdrawn when a call made by the user is not completed.

The present invention is directed to a method 25 of forming housings of this type and relates particularly to the method of forming the front portion 11. In the first step of the invention a substantially rectangular box-like blank as illustrated in Fig. 2 is simultaneously punched from sheet metal and drawn to form the top 30 25, front wall 26, angularly disposed portion 27, bottom 28 and sides 29 and 30. After the blanking and drawing operation the edges 35, 36, 37 and 38 of the top 25, bottom 28 and sides 29 and 30, respectively, are trimmed to remove any 35 rough edges formed in the drawing operation and to flatten the surfaces so that, when the front portion 11 and rear portion 12 are assembled there will be no cracks between them 40 indicating the joint.

In Fig. 3, the next step of the method is illustrated which comprises perforating two holes indicated by the numerals 39 and 40. The hole 40 will later be formed to receive the door (not shown) and the hole 39 which is a comparatively narrow slot will later be formed to comprise the coin chute opening 31.

45 After the coin chute opening 31 has thus been partially made as indicated at 39 and the door opening 13 has been partially made as indicated at 40 in Fig. 3, a preliminary drawing operation is performed on the edges of the hole 40 and simultaneously a shearing operation is performed to enlarge the hole 39. As shown in Fig. 4 the 50 55

edges of the hole 40 are in this operation, drawn back from the face of the front wall 26 as shown at 41 and the front wall 26 is sheared along what in the finished part will be the top and bottom 5 of the coin chute opening 31 as indicated at 42 and the sheared metal is bent at an angle to the plane of the front wall 26 as indicated at 43. The edges of the hole 40 are then sheared as 10 shown by the dotted lines at 44 in Fig. 4 as a preliminary step to the final operation of forming the front portion 11.

The final step in forming the front portion 11 comprises completing the bending of the portion indicated at 43 (Fig. 4) to a plane at right 15 angles to the plane of the front wall 26 as shown at 45 and swaging the edges of the door opening 13 (Fig. 5). The final step results in forming the seat for the door with a flat surface 46 20 against which the door will rest and also results in thickening and strengthening the seat as shown at 47 thereby making it more difficult to force the door open after it has been locked in place. Simultaneously with the swaging of the 25 edges of the door opening an embossing 48 (Fig. 1) is formed in the front wall 26.

If any of the hereinbefore described operations have distorted or roughened the edges 35, 36, 37, and 38, an additional trimming operation may be performed to straighten the edges. After the 30 front portion 11 has thus been formed it may be secured to the rear portion 12 by welding a strip 50 to it and to the rear portion as shown in Fig. 1 and a partition 51 may be secured to the bottom of the rear portion 12 and to the portion of the 35 front wall 26 which is bent at right angles to the front wall and indicated at 45 (Figs. 1 and 5).

What is claimed is:

1. The method of forming the front of a coin box for telephone pay stations which comprises

forming a blank having a front wall and top, bottom and side flanges, perforating two openings in the front wall of the blank, enlarging one of said openings by shearing and folding the metal adjacent thereto at an angle to the front wall, and drawing the metal adjacent the edges of the second opening out of the plane of the front wall, and swaging the edges of said second opening to form a door seat and to thicken the material adjacent the edges along a predetermined line.

2. The method of forming the front of a coin box for telephone pay stations comprising forming a rectangular blank having a front wall and top, bottom and side flanges, perforating two 15 openings in the front wall, enlarging one of said openings by shearing and folding the metal adjacent thereto at an angle to the plane of the front wall, drawing the metal adjacent the edges of the other opening out of the plane of the 20 front wall, swaging the edges of the last mentioned opening to provide a door seat, and again bending the metal previously bent to a position at right angles to the plane of the front wall.

3. The method of forming the front of a coin 25 box for telephone pay stations comprising forming a rectangular blank having a front wall and top, bottom and side flanges, perforating two 30 openings in the front wall, enlarging one of said openings by shearing and folding the metal adjacent thereto at an angle to the plane of the front wall, drawing the metal adjacent the edges of the other opening out of the plane of the front wall, and simultaneously swaging the edges of the last mentioned hole to provide a door seat 35 and again bending the metal previously bent to a position at right angles to the plane of the front wall.

IVAR A. MORBERG.
